(57) **CLAIM**

The ornamental design for a razor cartridge, as shown and described.

DESCRIPTION

FIG. 1 is a perspective view taken from the front of an embodiment of a razor cartridge of my new design; FIG. 2 is a perspective view taken from the rear of the razor cartridge;

FIG. 3 is a front elevation view thereof, the rear elevation view being identical;

FIG. 4 is a top edge view thereof;

FIG. 5 is a bottom edge view thereof;

FIG. 6 is a side elevation thereof;

FIG. 7 is a perspective view taken from the front of an alternate embodiment of a razor cartridge of my new design;

FIG. 8 is a perspective view taken from the rear of the razor cartridge;

FIG. 9 is a front elevation view thereof, the rear elevation view being identical;

FIG. 10 is a top edge view thereof;

FIG. 11 is a bottom edge view thereof;

FIG. 12 is a side elevation thereof;

FIG. 13 is a perspective view taken from the front of an alternate embodiment of a razor cartridge of my new design; FIG. 14 is a perspective view taken from the rear of the razor cartridge;

FIG. 15 is a front elevation view thereof, the rear elevation view being identical;

FIG. 16 is a top edge view thereof;

FIG. 17 is a bottom edge view thereof;

FIG. 18 is a side elevation thereof;

FIG. 19 is a perspective view taken from the front of an alternate embodiment of a razor cartridge of my new design; FIG. 20 is a perspective view taken from the rear of the razor cartridge;

FIG. 21 is a front elevation view thereof, the rear elevation view being identical;

FIG. 22 is a top edge view thereof;

FIG. 23 is a bottom edge view thereof; and,

(Continued)

FIG. 24 is a side elevation thereof.

The broken lines shown in the drawings illustrate portions of the razor cartridge and form no part of the claimed design.
